UNITED STATES PATENT OFFICE.

ABRAHAM SCHWARTZMAN, OF ST. LOUIS, MISSOURI.

DESIGN FOR A JEWELRY-RING.

48,873.

Specification for Design.

Patented Apr. 11, 1916.

Application filed February 11, 1916. Serial No. 77,808. Term of patent 3½ years.

To all whom it may concern:

Be it known that I, ABRAHAM SCHWARTZMAN, a citizen of the United States, residing at the city of St. Louis, State of Missouri, have invented a certain new, original, and ornamental Design for Jewelry-Rings, of which the following is a specification, reference being had to the accompanying drawing, forming a part thereof, in which—

Figure 1 is a plan view of a jewelry ring embodying my new design; Fig. 2 is an end elevational view thereof; and Figs. 3 and 4 are opposite side views of the same.

I claim—

The ornamental design for a jewelry ring substantially as shown.

ABRAHAM SCHWARTZMAN.
